UNITED STATES PATENT OFFICE.

EDMOND P. DE BERRY, OF BERKELEY, CALIFORNIA, ASSIGNOR TO FOARD STARTER MANUFACTURING CO., OF SAN FRANCISCO, CALIFORNIA, A CORPORATION OF CALIFORNIA.

STARTING DEVICE FOR AUTOMOBILES.

1,150,421.

Specification of Letters Patent.

Patented Aug. 17, 1915.

Application filed September 8, 1914. Serial No. 860,573.

To all whom it may concern:

Be it known that I, EDMOND P. DE BERRY, a citizen of the United States, residing at Berkeley, in the county of Alameda and State of California, have invented new and useful Improvements in Starting Devices for Automobiles, of which the following is a specification.

The invention relates to engine cranking devices, and particularly to a manually operable starter for automobiles.

It is an object to provide a cranking device readily attachable to standard automobiles without expensive alteration or machinery of the same, to provide a device which is simple, reliable and particularly designed to safely release in the event of a "kick-back" of the engine.

The invention consists of the parts and the combination and construction of parts as hereinafter more fully described and claimed, having reference to the accompanying drawings, in which—

Figure 1 is a front elevation of the device, as applied to a crank shaft. Fig. 2 is a plan view thereof.

At 2 is indicated a crank shaft upon which is pinned, keyed or otherwise fastened a collar 3 having a pulley face 4, a toothed face 5 and a clutch face 6. Encompassing the collar is a ring 7 forming the hub of a knuckle jointed lever 8, the outer end of which is connected by a suitable device, as a cable 9 to a hand-lever 10 mounted for convenient operation by the operator of the engine or vehicle.

On the section of the lever above the pivot joint 11 is pivoted at 12 a link 13, the lower end of which is pivoted at 13' to a pawl 14, which is in the plane of the ratchet teeth. The pawl 14 is pivoted at 15 on the hub section of the lever 8. A spring 16 connecting the pawl 14 and the hub section operates to hold the pawl-end clear of the ratchet teeth and to rock the lever-end backward on its pivot 11.

When installed upon an engine the lever 8 is connected to a fixture or part of the frame by a suitable spring 17, the function of which is to draw the lever over to one side and hold it in readiness to be operated crank-like with the revolution of the shaft 2.

The operation of the device is as follows: The hand-lever 10 is moved to exert a pull on the cable 9 which draws over the lever 8.

The first effect of the cable pull is to rock the lever-end and throw the pawl 14 into engagement with the ratchet face. As the pull continues the tension of the return spring 17 is overcome and then the entire lever 8 swings with the pawl 14 engaging the ratchet and turning the shaft. Efficient motors are easily started by this device on a half turn, but in event of failure the lever 8 is oscillated until the engine starts. In event of a "kick-back" by the engine, the pawl 14 is disengaged by the abutment of a part 14' thereon with a stationary member 14" arranged at the normal idle position of the lever 8 and pawl 14.

The device is simple, practicable and readily installed and is coöperable with the regular starting crank 18 which has a clutch member 19 engageable with the clutch 6 of the collar 3. Thus the engine may be started either by the lever 8 or the common crank, each being independent of the other.

Oiling of the collar and ring is provided for by a grease cup 20 attached to the ring. Balls 21 to form a ball bearing between the ring and collar may be inserted through the oiling port when the grease cup is detached.

Having thus described my invention what I claim and desire to secure by Letters Patent is—

1. In combination with the engine shaft, a member on said shaft having peripheral teeth, a sectional lever having a hub rotatably mounted on said member, a pawl pivoted to the inner section of the lever and being engageable with said teeth, the outer lever section having an upwardly extending projection, a link above the lever pivoted to said projection and to the pawl, a cable connected to the outer lever section, a spring for tensioning the inner lever section, a depending part on the pawl, and a stationary member beneath the pawl for engaging said depending part thereof to rock the pawl to inoperative position upon rearward movement of the shaft.

2. In combination with the engine shaft, a member on said shaft having peripheral teeth, a sectional lever the inner section of which is in rotatable connection with the shaft, a pawl pivoted to said inner lever section and being engageable with the teeth of said member, means to tension the inner lever section, a connection between the upper end of the pawl and the outer lever section,

and means to operate the outer lever section whereby to cause said connection to actuate the pawl into engagement with the teeth of said member.

5. 3. In combination with the engine shaft, a member on said shaft having peripheral teeth, a sectional lever the inner section of which is in rotatable connection with the shaft, a pawl pivoted to said inner lever section and being engageable with the teeth of said member, means to tension the inner lever section, a connection between the upper end of the pawl and the outer lever section, a depending part on the pawl, a stationary
- 10.

member beneath the pawl engageable with 15 said depending part upon backward rotation of the shaft to disengage the pawl from the teeth, and a cable connected to the outer lever section for moving the connection of said outer section with the pawl to cause the 20 latter to engage the teeth of said member.

In testimony whereof I have hereunto set my hand in the presence of two subscribing witnesses.

EDMOND P. DE BERRY.
